[57] **CLAIM**

The ornamental design for a grill scraper, as shown and described.

DESCRIPTION

FIG. 1 is a perspective view of the grill scraper;

FIG. 2 is a top plan view of the grill scraper;

FIG. 3 is a bottom plan view of the grill scraper;

FIG. 4 is a left side elevational view of a grill scraper;

FIG. 5 is a right side elevational view of the grill scraper;

FIG. 6 is a front elevational view of the grill scraper;

FIG. 7 is a rear elevational view of the grill scraper.

The surface shading of the figures is fragmentarily shown for convenience of illustration, it being understood that the shading is uniformly continuous over the surface which it appears.
